UNITED STATES PATENT OFFICE

166,773

END LINK FOR A WRIST WATCH BRACELET

Eugen Prestinari, Short Hills, N. J., assignor to
Gemex Company, Union, N. J., a corporation of
New Jersey

Application June 4, 1951, Serial No. 15,413

Term of patent 3½ years

(Cl. D45—4)

To all whom it may concern:

Be it known that I, Eugen Prestinari, a citizen of the United States and a resident of Short Hills, Essex County, New Jersey, have invented a new, original, and ornamental Design for an End Link for a Wrist Watch Bracelet, of which the following is a specification, reference being had to the accompanying drawing, forming part hereof, in which:

Fig. 1 is a top plan view of an end link for a wrist watch bracelet embodying my new design;
Fig. 2 is a bottom plan view;
Fig. 3 is a side elevation;
Fig. 4 is a section taken on line 4—4 of Fig. 1; and,

Fig. 5 is an end view as viewed from the left of Figs. 1 and 3.

I claim:

The ornamental design for an end link for a wrist watch bracelet, substantially as shown.

EUGEN PRESTINARI.
